ATTORNEY

UNITED STATES PATENT OFFICE.

SYLVESTER DUGAN, OF TARENTUM, PENNSYLVANIA.

DESIGN FOR A POST-CARD.

45,414.

Specification for Design.

Patented Mar. 17, 1914.

Application filed January 21, 1914. Serial No. 813,590. Term of patent 3½ years.

To all whom it may concern:

Be it known that I, SYLVESTER DUGAN, a citizen of the United States of America, residing at Tarentum, in the county of Allegheny and State of Pennsylvania, have invented a new, original, and ornamental Design for Post-Cards, of which the following is a specification, reference being had to the accompanying drawing, forming part thereof.

The figure is a plan view of a post card, showing my new design.

I claim:

The ornamental design for a post card, as shown.

SYLVESTER DUGAN.

Witnesses:

LAURENCE SEFTON,
J. F. HEPLER.
